Attorney.

UNITED STATES PATENT OFFICE

CARL E. NORIN, OF JERSEY CITY, NEW JERSEY, ASSIGNOR TO UNDERWOOD ELLIOTT FISHER COMPANY, OF NEW YORK, N. Y., A CORPORATION OF DELAWARE

TYPEWRITING MACHINE

Application filed August 15, 1927. Serial No. 213,131.

This invention relates to means for holding labels, cards, or the like on the type-writer-platen. Such devices are usually made of resilient sheet-metal (substantially 5 in the form of open sleeves) to be clasped around the platen to rotate therewith. The holder is usually self-sustaining or provided with means for gripping the platen, and it also holds independently the card or label 10 upon the platen.

According to the present invention, a main clasp extends more than half way around the platen, to enable the device to securely retain itself upon the platen, and a more 15 yielding paper-clip or finger is normally tensioned upon the platen and has the form of a frame surrounding one end of the main clasp, both the frame and the main clasp preferably being inexpensively and compactly struck out of a single sheet of resilient material forming a light structure. The card or label is inserted by its lower margin between the forward gripping edge of 20 said resilient frame and the platen, said frame, as a whole, becoming separated slightly from the platen, without weakening the firm grip of the main clasp around the platen.

Preferably two platen-clasping tongues, 25 side by side, are stamped out of an open sheet-metal sleeve adjacent a longitudinal edge thereof, in such a way that an E-shaped frame is created to serve as a paper-clip, said frame surrounding said tongues. The 30 frame is formed with the three parallel cross-bars extending out of the body of said sleeve and alternating with said tongues; and a longitudinal bar completes the E-shape, joining the three parallel bars in 35 front of the tips of said tongues. Said longitudinal bar forms the gripping edge 40 to hold the paper. This device affords great flexibility and adaptability to the platen.

Another feature consists in the provision 45 of outwardly-raised portions as ribs or wards upon the main clasp, so as to keep certain typewriter parts adjacent the platen away from the yielding frame, to secure unrestrained flexibility thereof within certain 50 limits, so that a card or label may be readily

inserted and held in place without danger of the pressure of the frame being altered.

The device is reliable in operation and easily attachable and detachable.

The invention is shown to be applied to 55 an Underwood portable typewriter.

Other features and advantages will hereinafter appear.

In the accompanying drawings,

Figure 1 is a partially sectioned perspective view of the detached novel label-holding device. 60

Figure 2 is an end view of the detached label-holding device.

Figure 3 is a cross-sectional elevation, 65 showing the novel label-holder mounted in place upon the platen when a card or label is being inserted, and showing ribs provided upon the holder being effective to keep the usual paper feed-rolls and the 70 front scale out of contact with the work-gripping yielding frame.

Figure 4 is a perspective view, showing the novel device clasped around the platen with a card inserted in writing position, 75 said card abutting the tips of platen-gripping tongues as a bottom gage. The usual front scale is partly broken away to more plainly disclose the ribs in their action of warding the scale away from the flexible 80 frame of the label-holder.

Figure 5 is a cross-sectional elevation to illustrate a novel manner of detaching the device from the platen.

Referring in particular to Figure 1, the 85 novel card-holder 10 substantially has the contour of a plain open sleeve and is made of resilient sheet-metal to be clasped around a platen 11 (see Figure 3) of a typewriter. The open sleeve has longitudinal edges 12 90 and 13 and sloped edges 14 at the sides, thereby forming two opposed tapers having their base at a longitudinal central portion 15 of said sleeve and their heads at said edges 12 and 13 thereof. The holder is, however, adapted for the double task of rather firmly gripping the platen, and, on the other hand, of more resiliently holding cards or labels to be written upon. To this end, there are stamped into the sleeve two U- 100

shaped slots 16 so as to create two relatively wide tongues 17, which, together with the body-part 18 of the sleeve, are to securely grip the platen wherever said sleeve is attached thereto, and also to create an E-shaped frame 19 around the two tongues which is to serve as a paper-clip for attaching cards or labels to the platen, said E-shape including three relatively narrow parallel cross-bars 20 extending from the body-part 18 and alternating with the tongues 17, and a longitudinal bar 21 in front of the tips of the tongues and joining the ends of said cross-bars in completion of the E-shape. The yielding paper-clip in the form described above affords a desired large paper-gripping edge in conjunction with comparatively large platen-gripping front edges. It is flexible and well adaptable to the platen, yet effectively resisting distortion. The whole arrangement is, over prior constructions of similar character, compact and handy.

Figure 2 more clearly illustrates the differentiated springing and gripping qualities of the holding device. The device substantially conforming to the curvature of the platen is shown in unstressed condition to have the tongues 17 normally deviate from the circular shape of the platen just far enough inwardly to enable the clasp, when being distended and sprung around the platen, to securely hold the device in place thereon, while the yielding paper-gripping frame 19 only slightly engages the circumference of the platen and will not exert considerable pressure upon the platen, although sufficient to hold the card or label thereon for the purpose of writing.

According to the invention, a card or label holder of the character described may be built advantageously of special material, as phosphor bronze, which, having the required springiness, does not need hardening or finishing. Such material therefore furnishes an inexpensive pressed product of shape and springing qualities as accurate as required for the purpose of effective and reliable operation, and undisturbed by distortion such as encountered with hardened material.

The label-holder, when attached to the platen, is shown in Figure 3 engaging the lower part of the platen, the yielding frame then being in front of the platen to show a card 22 when being inserted and gripped by its lower margin. Inserting a small work-piece by its lower margin is convenient and only requires a fraction of a full turn of the platen backwardly for positioning. The gripping edge 12 of the yielding frame is beveled, as shown, to facilitate insertion of the card.

It moreover appears from Figure 2 that ribs 23, according to the invention, provided upon the tongues 17 and reinforcing the

same, are effective in keeping the usual feed-rolls 24 and the usual front scale 25 out of contact with the paper-gripping frame 19. The front scale, in a manner well known in portable typewriters, is screwed and flanged to an apron 26, which is pivoted at 27 upon a platen-carriage 28, while the paper-feed-rolls 24 are journaled in coiled ears 29 struck out of said apron 26. A spring 30 acts upon the apron to hold the rollers in engagement with the platen 11, and a feed-roll-release mechanism at 31 is indicated in dot and dash.

As the ribs 23 clear the way, as shown, they afford unrestricted flexibility of the yielding frame between the warded off front scale or feed-rolls and the platen, so that the card or label 22 can be readily introduced between the gripping edge 12 of the yielding frame and the platen 11, said card being held by the frame while the platen is rotated backwardly to bring the label down to the printing line, as indicated in Figure 4.

When the label is inserted its bottom edge rests against the tips of the clasp-tongues 17 (see Figure 4), which therefore are a bottom gage for the label, whereby the forward ends 31a of the ribs 23, forming part of the abutment, serve to prevent the card from being thrust over the tongues, that is, beyond the gage line. The label is held in proper position throughout the forward and backward rotation of the platen, and it should be understood that the top edge of the label may be held against the platen by usual paper-fingers, rollers or the like (not shown in the drawings).

Due to its compactness the device is easy to handle. Having straight longitudinal edges and rounded corners, the clasp readily slips over the platen without danger of scratching or injuring the platen-surface, and grips the platen for a firm seat. The tapering of the holder from its central body-portion towards its extremities 12 and 13, as mentioned above, increases the flexibility of the holder towards said extremities and thereby facilitates its application to the platen, said central body-portion being wide enough to properly seat the device as a whole upon the platen.

Moreover, the device, as herein described, will largely facilitate the detachment thereof, which generally is troublesome due to the flatness and close fit of such appliances and due to liability of scratching the platen-surface.

According to a novel method of detaching the label-holder, the platen, according to Figure 5, is rotated backwardly, as indicated by arrow 32, until the longitudinal edge 13 of the clasp engages lengthwise the edge of the movable front scale 25, which, by the operator's finger, is pressed against the platen. A slight additional turn given

to the platen 11 will cause the holder to smoothly slip off the platen without excessive manual force being applied thereby injuring the platen-surface, and with the 5 yielding frame 19 not offering obstructive resistance.

Variations may be resorted to within the scope of the invention, and portions of the improvements may be used without others.

10 Having thus described my invention, I claim:

A work sheet holder comprising a body portion and a resilient E shaped frame extending therefrom, a plurality of less resili-
15 ent tongues extending between the branches of the E shaped frame and adapted to clasp a typewriter platen, the outer ends of said tongues forming abutments for a work sheet while the longitudinal outer edge of the E
20 shaped frame extends in front of and around said tongues and is adapted to clasp said work sheet.

CARL E. NORIN.
